Merchant and Kilgore

UNITED STATES PATENT OFFICE.

SAMUEL B. SKLAR, OF MINNEAPOLIS, MINNESOTA.

SMOKER'S CABINET.

Application filed October 31, 1927. Serial No. 229,996.

My present invention has for its object to provide a smoker's cabinet for holding cigars, cigarettes, matches and an ash tray where they are within easy access, but at the same time when the cabinet is closed are covered and out of sight. The smoker's cabinet, whether closed or open, is artistic and has a very neat appearance, and while intended for general use, is especially adapted for the home or office where the same may be placed on a table or desk.

To the above end, generally stated, the invention consists of the novel devices and combinations of devices hereinafter described and defined in the claim.

In the accompanying drawings, which illustrate the invention, like characters indicate like parts throughout the several views.

Referring to the drawings:

20 Fig. 1 is a perspective view of the smoker's cabinet;

Fig. 2 is a view partly in plan and partly in horizontal section taken on the line 2—2 of Fig. 1, on an enlarged scale;

25 Fig. 3 is a view principally in transverse vertical section taken on the irregular line 3—3 of Fig. 2; and

Fig. 4 is a view corresponding to Fig. 3 with the exception that the doors are open.

30 The smoker's cabinet is formed from pressed sheet metal and comprises a rectangular shell 5 having a supporting base 6. This shell 5 is completely closed except at its two sides where there are relatively large door openings normally closed by doors 7 and 8. Said doors 7 and 8 are hinged at their ends to the shell 5, as indicated at 9, for outward swinging movement. Each door 7, 8, is provided near its top with a knob 10 by which the door may be held while opening and closing the same.

35 A cigar compartment 11 is rigidly secured to the inner face of the door 7 and has formed in its inner wall a relatively deep notch or finger passage 12 so that the cigars in said compartment may be easily removed. Said cigar compartment 11 has a lining 13 of felt or other suitable material.

40 On the inner face of the door 8 is a cigarette package holder comprising a pair of upright laterally spaced channel members 14 rigidly secured to the inner face of said door 8 at its intermediate portion with their

flanges turned toward each other. On the lower ends of the channel members 14 are inturned supporting flanges 15. These members 14 are of such size and so arranged as to support and hold a standard package of cigarettes. Also mounted on the inner face of the door 8 is a removable ash tray 16 detachably secured to one of the channel members 14 by a headed stud 17 which extends into a relatively deep notch 18 in said channel member 14. Obviously, by lifting the ash tray 16 from the door 8, the headed stud 17 will be withdrawn from the notch 18 and thereby releases the ash tray from said door.

Further secured to the inner face of the door 8 is a match box holder in the form of a horizontal member 19 having on its inner end an upstanding spring arm 20 for releasably holding a box of matches. A pin 21 on the horizontal member 19 is arranged to engage a match box proper at the time the same is placed in its holder and lift the same from its cover so that the matches can be easily removed from the box.

Simultaneous opening and closing movements are imparted to the doors 7 and 8 by upright relatively short levers 22 intermediate pivoted one to the ends of the shell 5. The ends of the levers 22 are connected indirectly to the doors by pairs of reversely-extended links 23. One pair of the links 23 at outer ends, is pivotally attached to the ends of the cigar compartment 11 and the outer ends of the other pair of links 23 are pivoted to inwardly projecting lugs 24 on the inner face of the door 8. One of these lugs 24 is so spaced that the ash tray 16 snugly fits between said lug and the respective channel member 14 and the other of said lugs is so arranged as to hold a box of matches on the holder 19—20 in contact with the adjacent channel member 14 and thereby prevent movement of said match box transversely of the holder 19—20. Obviously, when one of the doors 7, 8, is opened or closed, like movements are imparted to the other door by the connections 22—23.

Stop pins 25 on the ends of the shell 5 are arranged to be engaged by the levers 22 to limit the opening movement of the doors 7, 8.

What I claim is:

105 A smoker's cabinet comprising a shell

having a door opening, a door normally closing said opening and having on its back a pair of laterally spaced upright channel members, the webs of which at their lower ends are turned laterally inward, said channel members affording a holder for a package of cigarettes one of said channel mem-

bers having a notch in the upper end of its web, an ash tray having a headed stud extending into said notch and supporting the 10 ash tray from said channel member.

In testimony whereof I affix my signature.

SAMUEL B. SKLAR.
